UNITED STATES PATENT OFFICE.

ROGER H. CANFIELD, OF VIVIAN, LOUISIANA, AND CARL W. LEMON, OF MARIETTA, OHIO.

WRENCH.

1,194,271.

Specification of Letters Patent.

Patented Aug. 8, 1916.

Application filed February 16, 1916. Serial No. 78,730.

To all whom it may concern:

Be it known that we, ROGER H. CANFIELD and CARL W. LEMON, citizens of the United States, residing at Vivian, in the parish of 5 Caddo, State of Louisiana, and Marietta, in the county of Washington and State of Ohio, respectively, have invented certain new and useful Improvements in Wrenches; and we do hereby declare the following to 10 be a full, clear, and exact description of the invention, such as will enable others skilled in the art to which it appertains to make and use the same.

Our present invention relates to improvements in wrenches in which movable jaws are mounted in connection with a handle for operating the same to close upon the work and secure such jaws in clamping engagement during the operation of handling such 20 material as pipe and the like.

Heretofore wrenches of this character have very generally consisted of jaws pivoted in a frame and having tail pieces projecting to be engaged each by the handle of 25 the wrench, an example of which may be seen in the Patent No. 970,574, granted September 20, 1910, to J. F. Tiner, and entitled "Pipe wrench." Instead of having the handle of the wrench engage both tail pieces of 30 the pairs of jaws, it is the primary object of the present invention to so arrange the several parts of the wrench that the handle will engage but a single tail piece, operating the respective jaw directly and providing inter- 35 connecting means between the jaws for transmitting the closing motion of the jaw operated by the handle to its companion jaw in a manner that will afford equal pressure of the jaws on the work as developed 40 from the same leverage.

With these and other objects in view the invention consists in the novel details of construction and combinations of parts more fully hereinafter disclosed and partic- 45 ularly pointed out in the claims.

In the accompanying drawings forming a part of this application, and in which similar reference symbols indicate corresponding parts in the several views: Figure 1 is 50 an elevational view of a wrench constructed in accordance with our invention, and with the front plate removed and the jaws shown in open position. Fig. 2 is a similar view illustrating the jaws in closed position; and

Fig. 3 is an end elevational view of the im- 55 proved wrench.

Referring more particularly to the drawings, wherein one embodiment of the invention is illustrated, 1 and 2 designate the wrench jaws, they being provided with flaring noses 3 and 4 for engaging the work when applied and automatically opening the jaws to receive the same; the gripping faces of the jaws being of the semi-circular or other configuration indicated at 5 and 6 for 60 clamping round work, such as pipe or other objects to which wrenches of this type are usually fitted, it being understood that the gripping faces 5 and 6 of the jaws 1 and 2 may be provided with steel dies or rough- 65 ened surfaces for insuring excellent grip.

The jaws 1 and 2 in the preferred embodiment illustrated in the drawings, are formed integral with enlarged central body portions 7 and 8 and oppositely-projecting tail pieces 75 9 and 10, such body portions being fitted to rock on bolts 11 and 12 and between plates 13 and 14, the bolt heads being upset on the exterior of said plates for binding the same together.

The inner faces of the tail pieces 9 and 10 are cut away divergently, as indicated at 15 and 16, to provide sufficient space therebetween for receiving one end of a handle 17. The handle 17 is pivoted on a bolt 18, also 80 secured to the plates 13 and 14; and it will be appreciated by reference more particularly to Figs. 1 and 2 of the drawings, that the pivot point of said handle 17 is at approximately the inner end thereof, there being no projecting portion to engage one tail piece.

Between the body portions 7 and 8 of the jaws 1 and 2 are arranged some suitable means for transmitting the closing motion 95 of one jaw to that of its companion, so that when one tail piece is engaged by the handle 17, as indicated in Fig. 2, to move its corresponding jaw to close about the work, the other jaw 2 will be simultaneously operated to close without any direct connection with the handle 17, but merely through the instrumentality of the connecting means between the body portions, which, as indicated in the drawings, may be a tooth, 19, and 100 notch, 20, arrangement; the opposing faces of the body portions 7 and 8 to either side of the tooth 19 being inclined, as indicated

at 21 and 22, for permitting the free operation of the jaws in moving to open and closed position.

In operation, the wrench, being in substantially the position illustrated in Fig. 1, is applied to the work by bringing the flaring noses 3 and 4 into engagement therewith, which will automatically swing the jaws 1 and 2 about their pivots 11 and 12 to open 10 sufficiently to receive said work within the interior gripping faces 5 and 6. After the work has been received between the jaws 1 and 2, the handle 17 may be swung in either direction to engage either tail piece 9 or 10, 15 for instance, as indicated in Fig. 2, by way of example, the handle may be swung to the left into contact with the tail piece 9, and by such operation the jaw 1 will be rocked about its fulcrum 11 to close about the work. 20 Simultaneously with the closing movement of the jaw 1, the tooth 19 will be operative in conjunction with the notch 20 to swing the companion jaw 2 in the opposite direction to coöperate with the jaw 1 and close 25 about the work in substantially the manner shown in Fig. 2. When the wrench is to be disengaged the handle is moved to the central position, releasing the engaged tail piece, and by rearward movement the jaws 30 will readily separate and may be entirely withdrawn.

Although we have illustrated in the drawing and described the connecting means between the jaws as being a gear arrangement, 35 nevertheless other mechanical devices might be substituted therefor; and we do not otherwise wish to be limited to the details of construction herein shown and described except as may be required by the appended 40 claims.

We claim:

1. In a wrench, the combination with movable jaws, a single handle for said wrench in operative relation to actuate 45 either of said jaws singly, and means between said jaws for moving the companion

from the operated jaw, substantially as described.

2. In a wrench, the combination with movable jaws, a single handle for said wrench 50 in operative relation to actuate either of said jaws singly and selectively accordingly as the jaw is shifted in one or the other direction, and a gear connection between said jaws for simultaneously moving the companion from the operated jaw, substantially 55 as described.

3. In a wrench, the combination with movable jaws, flaring noses on said jaws, means for operating one jaw, and a gear connection 60 between said jaws for operating the companion jaw from the operated jaw, substantially as described.

4. In a wrench, the combination with movable jaws, tail pieces on said jaws, a handle 65 for engaging one tail piece only to move the respective jaw, and means for operating the companion jaw simultaneously with and from the moved jaw, substantially as described. 70

5. In an improved wrench, the combination of a frame, jaws pivoted in said frame, tail pieces on said jaws, a handle for engaging either tail piece to rock the respective 75 jaw, and a gear connection between said jaws connecting the same for simultaneous operation, substantially as described.

6. In an improved wrench of the character described, the combination of a frame, a pair of jaws pivoted in said frame, flaring 80 noses on said jaws, tail pieces projecting from said jaws, a handle pivoted in said frame and adapted to engage either tail piece to rock the respective jaw to closed 85 position about the work, and a tooth and notch connection between said jaws for connecting the same for simultaneous operation, substantially as described.

In testimony whereof, we affix our signatures.

ROGER H. CANFIELD.
CARL W. LEMON.
